GOLF BAG STAND

Glen H. Huber, Downers Grove, Ill.

Application November 1, 1954, Serial No. 466,111

1 Claim. (Cl. 248—96)

This invention relates to golf bags and more particularly to stands for attachment to golf bags, permitting them to stand in a semi-upright position.

It is an object of this invention to provide a portable stand capable of supporting a golf bag in a semi-upright position, and capable of folding compactly against the bag for carrying purposes.

A further object of this invention is to provide an improved stand for golf bags that has little weight and does not protrude unduly when folded for carrying.

Another object is to provide a golf bag stand with a simplified structure which is economical to manufacture.

Further objects and features of this invention, its mode of operation and its advantages, may be gathered from a reading of this specification together with an inspection of the accompanying drawing, in which:

Figure 1 is a view of the golf bag stand of this invention in its extended position, illustrating the manner in which it supports the golf bag;

Figure 2 is a similar view of the golf bag stand but in its folded position as it would be carried;

Figure 3 is a top view of the stand in its folded position looking along the line 3—3 (Figure 2), and it illustrates the manner in which the golf bag is attached; and

Figure 4 is an enlarged section along the line 4—4 and shows in more detail the structure and a spring clip for engaging and holding the leg of the stand in its folded position.

In the various views of the drawing similar elements are designated by the same reference numeral.

Referring to the drawing in further detail, it is seen that the stand comprises a supporting member 1, which is a channel preferably of aluminum, which may be secured along the side of the golf bag 2. A second channel 3 forms a leg and is pivotally mounted on the supporting channel 1. The leg channel 3 may pivot outwardly from the supporting channel 1 to form a standing position as illustrated in Figure 1, and it may be pivoted inwardly to lie closely along the side of the golf bag to form a carrying position as illustrated in Figure 2.

The supporting channel 1 is fitted with cross members 4 and 5 which provide a convenient means for attaching straps 6. The cross member 5 located at the lower extremity of the supporting channel 1 has a part turned at an angle of 90° to form a rest upon which the golf bag may be placed. The straps 6 may be of inexpensive web strapping material and are adapted to encircle the top and the bottom of the golf bag and hold it snugly against a supporting member 1.

To add stability and prevent the stand from tipping, a cross member 7 is mounted on the lower extremity of the leg channel 3. The ends of the cross member 7 are bent slightly inward (shown in Figures 3 and 4) and are therefore adapted to fit more snugly against the golf bag when in the folded or carrying position. This slightly bent structure of the cross member 7 has been found to be more compact in the folded position for carrying and at the same time it has been found that no degree of stability has been sacrificed.

2

The leg member 3 is an aluminum channel of somewhat greater cross section than the supporting channel 1. The spacing between the flanges of the leg channel 3 is great enough to permit the supporting channel 1 to nest therebetween when in the folded position.

The leg channel 3 is pivotally mounted to the supporting channel 1 by a pin 8 that extends through the flanges at the upper end of the leg channel 3 and also through the flanges of the supporting channel 1 which are disposed between the outer flanges of the leg channel. To provide a stop preventing the leg member 3 from pivoting at too wide an angle, the supporting channel 1 is notched at 9. As the leg channel 3 pivots outwardly, a portion thereof swings into and engages the notch at the proper angle.

A spring clip 10 is mounted about the supporting channel 1 and is positioned to engage and hold the leg channel 3 when it is in the folded position. The spring 10 offers enough force to hold the leg firmly against ordinary jostling and movement. On the other hand, the leg 3 is easily sprung loose from the clip 10 when it is desired to stand the golf bag upright.

This golf bag stand has been made to weigh less than the ordinary golf club, and it protrudes less than one inch from the side of the golf bag when in the folded position. It is designed to hold bags of various sizes and shapes and may be attached or detached therefrom by merely adjusting the straps 6.

Changes may be made in the form, construction and arrangement of the parts without departing from the spirit of the invention or sacrificing any of its advantages, and the right is hereby reserved to make all such changes as fall fairly within the scope of the following claim.

What is claimed is:

35 A stand for a golf bag adapted to support a bag in a substantially upright position comprising, a first elongated channel member adapted to extend longitudinally of a golf bag with the flanges extending away from the bag, spaced straps connected to said channel member adapted to detachably secure a golf bag to said member, a projecting member extending from the bottom of the first channel member in a direction opposite to the extending direction of said flanges, whereby said member is adapted to underlie the bottom of the golf bag and define a rest to prevent relative movement between the bag and stand when the stand is supporting the bag in a substantially upright position and space the bottom of the bag above the ground, a second elongated channel member having its flanges extending towards the golf bag and pivotally connected at its upper end to the upper end of said first channel member, said channel members being of substantially the same length, one of said channel members having a greater cross section than the other channel member, whereby when the channel members are in folded position the flanges of one channel member are nested within the flanges of the other channel member, a stabilizing bar transversely mounted at the lower free end of said second member, a yieldable clip on said first member adapted to hold said second member in folded position, and notches formed in the flanges of said first member adapted to engage the upper end of said second member and limit its pivotal movement away from said first member.
